(57) **CLAIM**

The ornamental design for a radome seam with embedded fastener nut as shown and described.

DESCRIPTION

FIG. 1 is a contextual perspective view of a radome seam with embedded fastener nut, showing our new design in the context of an associated radome;

FIG. 2 is a top perspective view of the radome seam with embedded fastener nut, taken at detail 2 in FIG. 1, showing our new design;

FIG. 3 is a front elevational view of the radome seam with embedded fastener nut, showing our new design in another environment of use;

FIG. 4 is a top plan view of the radome seam with embedded fastener nut, showing our new design in the environment of use of FIG. 2;

FIG. 5 is a bottom plan view thereof;

FIG. 6 is a further top perspective view thereof;

FIG. 7 is a bottom perspective view of the radome seam with embedded fastener nut, showing our new design in another environment of use; and,

FIG. 8 is a further bottom perspective view thereof.

The long dash-long dash broken lines of FIGS. 1-3 and 6-8 depict the limits of the enlarged views and form no part of the claimed design.

The dash-dot-dash boundary is provided in FIGS. 1-3 and 6-8 to define the outer bounds of the claimed design. The additional dash-dash broken lines in FIGS. 1-8 are for the purpose of illustrating portions of the radome seam with embedded fastener nut and environmental structure that form no part of the claimed design.

1 Claim, 4 Drawing Sheets
